UNITED STATES PATENT OFFICE.

JOHN M. POWERS AND JOHN L. BOYD, OF ST. LOUIS, MISSOURI.

WEATHER-STRIP FOR METAL FRAMES AND SASH.

No. 918,591.

Specification of Letters Patent.

Patented April 20, 1909.

Application filed February 4, 1907. Serial No. 355,668.

To all whom it may concern:

Be it known that we, JOHN M. POWERS and JOHN L. BOYD, citizens of the United States, and residents of St. Louis, Missouri, have invented certain new and useful Improvements in Weather-Strips for Metal Frames and Sash, of which the following is a specification containing a full, clear, and exact description, reference being had to the accompanying drawings, forming a part hereof.

Our invention relates to a weather strip for metal frames and sashes, and the object of our invention is to provide a simple, inexpensive, and easily installed metal weather strip, which is particularly applicable for metal window frames and sashes, and which when in use forms a practically air tight joint between the sash and the frame, and thus prevents dust, rain, and snow from entering the interstices between said sash and frame.

To the above purposes, our invention consists in certain novel features of construction and arrangement of parts, which will be hereinafter more fully set forth, pointed out in the claim, and illustrated in the accompanying drawings, in which:—

Figure 1 is a vertical section taken through the center of a window frame and showing the arrangement of the window strips thereon; Fig. 2 is a horizontal section taken on the line 2—2 of Fig. 1; Fig. 3 is a horizontal section taken on the line 3—3 of Fig. 1; Fig. 4 is a horizontal section taken approximately on the line 4—4, or at the point where the top rail of the lower sash and lower rail of the upper sash meet; Fig. 5 is a side elevation of the central portion of one of the strips which is positioned adjacent to the parting strip on the side of the window frame; Fig. 6 is a detail section of the section of weather strip which is positioned at the top of the window frame and against which the top rail of the upper sash engages; Fig. 7 is a detail section illustrating the strips which are arranged on the meeting rails of the sashes; Fig. 8 is a detail section showing the strip against which the bottom rail of the lower sash engages.

Referring by numerals to the accompanying drawings:—1 designates the sheet metal frame, constructed in the usual manner, and provided in its sides with the usual guide-ways 2, separated by the vertically disposed rib 3, which forms the parting strip, and in

which guide-ways operate in the usual manner the lower sash 4 and upper sash 5. These sashes are constructed of sheet metal, and formed on the edges are the projecting flanges 6, which fit against the corresponding shoulders formed in the frame 1.

7 designates the weather strip which is positioned at the bottom of the window frame, which strip is constructed of suitable resilient metal of inverted L-shape in cross section, and the horizontal portion of said strip is arranged on top of the shoulder at the front edge of the lower portion of the frame 1 with the vertical portion of said strip projecting downwardly in position to be engaged by the flange 6 on the lower edge of the bottom rail of the lower sash. The strip 7 being constructed of resilient metal will readily give when engaged by the flange 7, and, when the lower sash is closed, will frictionally engage against the face of the lower rail of the lower sash, and thus form a very tight joint between the lower rail of the lower sash and the window frame.

Arranged on the rear upper corner of the top rail of the lower sash is an inverted U-shaped strip 8, constructed of suitable sheet metal, and arranged on the front upper corner of the lower rail of the upper sash is a corresponding U-shaped strip 9, which strips engage and fit into one another when the sashes are closed, thus forming a tight joint between the meeting rails of the upper and lower sashes.

Fixed to the under side of the top of the window frame 1 and extending transversely between the ribs 3 is a vertically disposed rib 10, to which is secured in any suitable manner an inverted U-shaped strip 11, which extends between the sides of the window frame, which strip is constructed of suitable sheet metal and receives the flange 6 on the front upper edge of the top rail of the upper sash, thus forming a tight joint between the said top rail and the upper portion of the window frame.

Fixed in any suitable manner to each rib 3 is a strip 12, the rear edge of the upper half of which is bent to form a vertically disposed channel 13 which extends from a point opposite the top rail of the lower sash upwardly to the top of the window frame, and the front edge of the lower half of the strip 12 is bent to form a channel 14, which extends from a point opposite the lower rail of the upper sash to the bottom of the frame

1, and these channels receive the corresponding flanges 6 formed on the edges of the side rails of the window sashes, and form air and dust proof joints between said rails and the sides of the frame 1.

5 All of the strips constructed as described are preferably formed of sheet brass, or similar metal, and when properly constructed and installed, provide a very cheap, 10 simple, and convenient strip, and said strips do not in any way interfere with the free operation of either of the sashes.

We claim:—

15 The combination with a metal window frame, on the faces of the jambs of which are formed integral ribs, of metal strips

detachably seated on said ribs, the edges of which strips are bent into channels to receive portions of the side rails of the sashes operating in the window frame, and the 20 channel on the upper half of each strip being offset relative to the channel on the lower half of the strip.

In testimony whereof, we have signed our names to this specification, in presence of 25 two subscribing witnesses.

JOHN M. POWERS.
JOHN L. BOYD.
